United States Patent Office.

E. M. HENDRICKSON, OF BROOKLYN, NEW YORK.

Letters Patent No. 63,046, dated March 19, 1867.

IMPROVEMENT IN THE CONSTRUCTION OF SAFES.

The Schedule referred to in these Letters Patent and making part of the same.

TO ALL WHOM IT MAY CONCERN:

Be it known that I, E. M. HENDRICKSON, of Brooklyn, in the county of Kings, and State of New York, have invented a new and improved Burglar-Proof Safe and Vault; and I do hereby declare that the following is a full, clear, and exact description thereof, which will enable those skilled in the art to make and use the same, reference being had to the accompanying drawings, forming part of this specification, in which—

Figure 1 is a side sectional view of a portion of the wall of a safe or vault constructed according to my invention.

Figure 2, a plan or top view of the same.

Similar letters of reference indicate corresponding parts.

This invention relates to an improvement on that class of burglar-proof safes and vaults in which chilled cast-iron walls are employed in order to prevent an entrance being effected by means of drilling. The chilled cast-iron walls are a great safeguard, as they can only be drilled by hard labor and a considerable expenditure of time; but as there are cases in which burglars can manage to operate repeatedly upon safes and vaults, the latter, even when constructed with the cast-iron walls, are not unfrequently broken into. The object of this invention is to render the cast-iron walls more secure than hitherto, and to this end it consists in having the walls cast around soft iron or other soft metal wire, bent in spiral form, and so closely or compactly arranged or disposed within the wall that a drill cannot avoid being brought in contact with it. The softness of the wire offers but little resistance to the great pressure under which the drill is required to operate, and hence, when the drill reaches the soft wire, the latter gives or yields, and the drill will be deflected from its course and broken, it not being able, under the pressure required to drill the chilled cast iron, (which is about twenty-five thousand pounds,) to resist the strain brought upon it. It is well known to all artificers in metal that it is extremely difficult to drill through masses of metal not homogeneous throughout, as the drill, when it comes in contact with a soft mass, cuts or feeds itself too rapidly, and the only way to proceed in such cases is to graduate the feed or pressure so that it will be commensurate with the hardness of the portion of metal being operated upon. But in my improvement, this cannot be effected, as the drill will come in contact with a soft mass at once, which immediately gives way, and causes the drill to be broken or destroyed.

In carrying out my invention, I have the soft metal, in the form of spiral wire springs A, arranged vertically and horizontally; so as to form a compact mass of wire that the drill cannot avoid coming in contact with; this inserted in the mould, and the iron B cast around it with a chill. The inner side of the wall has a thin wrought-iron plate, C, secured to it by bolts or otherwise, in order to hold the cast-iron wall together in case of the latter being broken by hammering. This, however, is an old feature, and is not so important in this connection, as the coiled wires A serve to keep the cast iron together in case of being broken, or is at present used with the chilled cast-iron walls. This improvement has been practically tested, and is an entire success; it has been found impossible to drill through the wall, the drill having been broken in every effort.

Having thus described my invention, what I claim as new, and desire to secure by Letters Patent, is—

I do not claim constructing the walls of safes by casting molten iron upon and around wrought-iron wires, rods, or bars, as this is not new; but what I do claim as my improvement is, using for such purpose, and in the manner described, wires or rods, bent or coiled spirally, as herein shown and described.

The above specification of my invention signed by me this 20th day of March, 1866.

E. M. HENDRICKSON.
